UNITED STATES PATENT OFFICE.

JOHN ERNEST KENNEDY, OF MONTREAL, CANADA.

DESIGN FOR A WARDROBE-CASE.

SPECIFICATION forming part of Design No. 28,998, dated July 5, 1898.

Application filed June 8, 1898. Serial No. 682,952. Term of patent 7 years.

To all whom it may concern:

Be it known that I, JOHN ERNEST KENNEDY, a subject of Her Majesty the Queen of Great Britain, residing in the city of Montreal, in the county of Hochelaga, in the Province of Quebec, Canada, have invented and produced a new and original Design for a Wardrobe-Case, of which the following is a specification, reference being had to the accompanying drawing, forming part thereof.

The drawing is a perspective view of my wardrobe-case.

As shown in the drawing, the leading or material feature of my design consists of back and front panels A and B, connected together at the top by a round rod C, intermediately by a shelf D, and at the bottom by a shelf E. The shelf D has side supports *d*, and a portion

of the shelf is slightly rounded in contour, as at *d'*. The side supports for the shelf D have 20 curved ends and are of greater depth near the panels. The shelf E is provided with side supports or rails *e*, which are also of greater depth near the panels. The panel B is narrower than the panel A, and the shelf E is curved inwardly 25 on both sides to meet the panel B.

Having described my invention, what I claim as new, and desire to secure by Letters Patent, is—

The design for a wardrobe-case as herein 30 shown and described.

JOHN ERNEST KENNEDY.
